PULSE FORMING CIRCUIT

Walter B. Varnum, Collingswood, N. J., assignor
to Radio Corporation of America, a corporation
of Delaware

Application December 31, 1943, Serial No. 516,426

5 Claims. (Cl. 250—27)

1

My invention relates to the production of electrical pulses particularly for use in radio pulse-echo systems.

An object of the invention is to provide an improved method of and means for producing electrical pulses.

A further object of the invention is to provide a simplified pulse producing circuit.

A still further object of the invention is to provide an improved circuit for triggering a self-pulsed oscillator.

In one preferred embodiment of the present invention a sine wave voltage is applied to the anode and grid electrodes of a gas or vapor tube, the voltage applied to the grid being delayed by about 90 degrees for example. As a result, the tube breaks down (is ignited) so that the voltage at the tube anode has a wave form with a steep or nearly vertical slope. The voltage of this wave form is applied to the grid of a vacuum tube that has an inductance coil in its plate circuit whereby the current flow through the inductance coil builds up during about one-fourth of the sine wave cycle and then collapses suddenly upon the occurrence of the steep portion of the said wave form. This sudden collapse is due to the fact that the vacuum tube is driven to plate current cut-off at this instant and will be explained hereinafter. Thus a voltage pulse is produced across the inductance coil. This voltage pulse is utilized, in the particular example described herein, for triggering a self-pulsed radio-frequency oscillator.

The invention will be better understood from the following description taken in connection with the accompanying drawing in which the single figure is a circuit diagram of one embodiment of the invention.

Referring to the drawing, a sine wave voltage 10 having the frequency of the desired pulse repetition rate is supplied from a suitable source 11 to an amplifier tube 12. The amplified wave 10 is applied through a blocking capacitor 13 and a resistor 14 to the anode 16 of a grid controlled gas or vapor tube 17 such as a Thyratron which will not ignite or break down until a certain ratio exists between the voltage on the anode 16 and the voltage on the control grid 18. The cathode 19 of the tube 17 is grounded.

The sine wave 10 is applied to the grid 18 through a phase shift or delay circuit comprising resistor-capacitor sections 21—24 and 22—26 and through a grid current limiting resistor 23. The amount of delay introduced is such as to make the tube 17 ignite at about the time the voltage on the anode 16 is a maximum. The resulting

voltage on the anode 16 has the wave form shown by the graph 27. It will be noted that this voltage wave has a steep portion 27' which is produced at the instant of ignition of the tube 17.

The anode 16 is coupled through a capacitor 31 to the control grid 32 of a vacuum tube 33. A suitable negative bias (—C) may be applied to the grid 32 through a filter resistor 35 and a grid leak resistor 40. A filter capacitor is shown at 35'. The tube 33 may be a pentode having a directly heated cathode 34, an anode 36, a suppressor grid 37, a screen grid 38 and the control grid 32. Filament heating current is supplied to the cathode 34 through a transformer 39. A center tap on the secondary of transformer 39 is connected to ground through a resistor 41 of only a few ohms resistance that is provided so that an oscilloscope may be connected thereto across to observe the wave form of the tube current. Resistor 41 is bypassed by a capacitor 42.

The D.-C. operating voltage (+B) is applied to the anode 36 through a choke coil 43 across which there will appear a voltage pulse 44 when the current flow therethrough is suddenly interrupted.

The operation of the circuit in producing the pulse 44 is as follows:

The voltage wave 27 is of sufficient amplitude to drive the grid 32 of the tube 33 positive whereby there is a flow of grid current as the wave 27 increases in amplitude. This grid current charges the coupling capacitor 31. At the instant the vapor tube 17 breaks down to produce steep wave portion 27', the anode-to-cathode impedance of tube 17 becomes very small so that the capacitor 31 is effectively connected between the control grid 32 and the cathode 34 of the tube 33. Therefore, the charge on capacitor 31 instantly biases the tube 33 beyond anode current cut-off and the anode current that has been flowing through the choke coil 43 is suddenly interrupted whereby the voltage pulse 44 is produced.

As soon as the vapor tube 17 deionizes, its impedance becomes so high, that it is practically an open circuit and the voltage of capacitor 31 is no longer applied between the cathode 34 and grid 32. However, the negative portion of the wave 27 now holds the tube 33 at plate current cut-off until on the next cycle of the wave 27 the instantaneous voltage increases sufficiently to permit anode current flow through the choke coil 43 again. As the instantaneous value of the wave 27 rises further, the value is reached where there is the aforementioned grid current flow which charges the capacitor 31, and then near the maximum voltage of wave 27 the tube 17 ignites to

produce the next pulse 44. The current flow through the tube 33 and choke coil 43 during the above described operation is shown by the graph 46. A resistor 47 may be connected between ground and the junction point of capacitor 13 and resistor 14 in order to provide a path through which the charge on capacitor 31 may continue to leak off after the tube 17 has deionized and to provide a direct-current connection from the grid of vapor tube 17 to ground.

In the example illustrated, a pulse-forming delay line or network 51 is employed to control the duration of a pulse 52 of radio-frequency energy which is produced by a self-pulsed oscillator 53. The pulse 44 is applied to the grid of the oscillator 53 and to one end of the network 51 through a blocking capacitor 54. The network 51 comprises series inductors 51a and shunt capacitors 51b. The pulse 44 triggers the oscillator 53 and at the same time a pulse of oscillator grid current travels down the network 51 to the open end where it is reflected back. The reflected voltage from the network 51 blocks the oscillator 53 whereby there is produced the R.-F. pulse 52 having a duration equal to the time required for a voltage wave to travel down the network 51 and back.

The oscillator 53, which is indicated only schematically in the drawing, may be of the type described in application Serial No. 460,670; filed October 3, 1942, in the name of Carroll D. Kentner, and entitled Multi-tube self-pulsing transmitter. This particular oscillator is of the tuned grid-tuned cathode type and is adjusted to self-pulse or block at a lower frequency than the one desired. This adjustment of the self-blocking time is made by adjusting a grid resistor 56. The triggering pulses 44 then control the pulsing rate of the oscillator exactly.

From the foregoing it will be apparent that I have provided a simple and effective pulse producing circuit, and that I have also provided an improved circuit for triggering a self-pulsed oscillator.

I claim as my invention:

1. An electrical pulse producing circuit comprising a vacuum tube having an anode, a grid and a cathode, an inductance coil through which a direct-current voltage is applied to said anode, a gas or vapor tube having an anode, a control electrode and a cathode, means for applying a periodic voltage to the anode of said vapor tube, means for applying a periodic voltage to said control electrode to ignite said vapor tube after the instantaneous voltage on the anode of the vapor tube reaches a substantial value, and means including a coupling capacitor for coupling the anode and cathode of said vapor tube to the grid and cathode of said vacuum tube, respectively, the voltage applied to the control grid of said vacuum tube having sufficient amplitude to drive said control grid positive whereby said coupling capacitor is charged by a flow of grid current and whereby said vacuum tube is driven to anode current cut-off when said vapor tube ignites thereby producing a voltage pulse across said inductance coil.

2. An electrical pulse producing circuit comprising a vacuum tube having an anode, a grid and a cathode, an inductance coil through which a direct-current voltage is applied to said anode, a gas or vapor tube having an anode, a control electrode and a cathode, means for applying a sine wave voltage to the anode of said vapor tube,

means for applying a voltage to said control electrode to ignite said vapor tube after the instantaneous voltage on the anode of the vapor tube reaches a substantial value, and means including a coupling capacitor for coupling the anode and cathode of said vapor tube to the grid and cathode of said vacuum tube, respectively, the voltage applied to the control grid of said vacuum tube having sufficient amplitude to drive said control

grid positive whereby said coupling capacitor is charged by a flow of grid current and whereby said vacuum tube is driven to anode current cut-off when said vapor tube ignites thereby producing a voltage pulse across said inductance coil.

3. An electrical pulse producing circuit comprising a vacuum tube having an anode, a grid and a cathode, an inductance coil through which a direct-current voltage is applied to said anode, a gas or vapor tube having an anode, a control electrode and a cathode, means for applying a sine wave voltage to the anode of said vapor tube, means for applying a voltage to said control electrode to ignite said vapor tube after the instantaneous voltage on the anode of the vapor tube reaches a substantial value, and means for coupling the anode and cathode of said vapor tube to the grid and cathode of said vacuum tube, respectively, said coupling means including a capacitor connected between the anode of said vapor tube and the grid of said vacuum tube, the voltage applied to the control grid of said vacuum tube having sufficient amplitude to drive said control grid positive whereby said coupling capacitor is charged by a flow of grid current and whereby said vacuum tube is driven to anode current cut-off when said vapor tube ignites thereby producing a voltage pulse across said inductance coil.

4. An electrical pulse producing circuit comprising a vacuum tube having an anode, a grid and a cathode, an inductance coil through which a direct-current voltage is applied to said anode, a gas or vapor tube having an anode, a control electrode and a cathode, means for applying a sine wave voltage to the anode of said vapor tube and to said control electrode with the sine wave voltages on said anode and said control electrode out of phase whereby said vapor tube ignites after the instantaneous voltage on the anode of the vapor tube reaches a substantial value, and means including a coupling capacitor for coupling the anode and cathode of said vapor tube to the grid and cathode of said vacuum tube, respectively, the voltage applied to said control grid having sufficient amplitude to drive said control grid positive whereby said coupling capacitor is charged by a flow of grid current and whereby said vacuum tube is driven to anode current cut-off when said vapor tube ignites thereby producing a voltage pulse across said inductance coil.

5. An electrical pulse producing circuit comprising a vacuum tube having an anode, a grid and a cathode and having an anode circuit and a grid circuit, an inductance coil in said anode circuit through which the anode current of said tube flows, a gas or vapor tube having a control electrode and having an anode coupled to said grid circuit through a capacitor and also having a cathode connected to the cathode of said vacuum tube, and means for applying a sine wave voltage to the anode of said vapor tube and to said control electrode with the voltage on said control electrode delayed.
